UNITED STATES PATENT OFFICE

2,437,399

MULTIPLE AIRSCREW DRIVEN FROM A
COMMON SHAFT

James F. Morgan, Orlando, Fla.

Application January 25, 1945, Serial No. 574,571

7 Claims. (Cl. 170—135.5)

1

This invention relates to a multiple air screw, comprising a plurality of blades adapted to be driven from a common shaft. A primary object of this invention is the provision of an improved air screw, including multiple blades driven from a common source of power, adapted to improve the efficiency of the air screw.

An additional object of this invention is the provision of an air screw, adapted for use as either a propulsion mechanism for air craft, or for use in a supercharger, speed sprayer, ventilating fan, or the like.

A further object of the invention is the provision of such a device wherein all the blades of the multiple air screw are adapted to rotate in the same direction, but each has a different speed, size and pitch.

As conducive to a clearer understanding of this invention it may here be pointed out that in the ordinary or conventional air screw or propeller rotating about a fixed shaft there is an area of relatively low efficiency. In only one point in the arc of rotation of such an air screw does it run in optimum speed, namely adjacent the tip thereof, and there is an area of progressively lowered efficiency, and correspondingly lowered speed as the blades approach the hub. An object of this invention is to provide a plurality of rotatable air screws mounted on a common shaft, each successive air screw adapted to provide increased efficiency in the area wherein the efficiency and speed of the corresponding or first air screw is lowered. The means for accomplishing this operation comprise a plurality of air screws in aligned relation, mounted on a common shaft, and each designed to operate within the area of lowered efficiency of the next forward set of blades.

Other objects reside in the combinations of elements, arrangements of parts, and features of constructions, all of which will be more fully pointed out hereinafter and disclosed in the accompanying drawings wherein there is shown a preferred embodiment of this inventive conception.

In the drawings:

Figure 1 is a transverse longitudinal sectional view taken substantially along the center line of the driving shaft for a multiplicity of air screws, constructed in accordance with the instant invention.

Figure 2 is a sectional view taken substantially along the line 2—2 of Figure 1 as viewed in the direction indicated by the arrows, and

Figure 3 is a front elevational view of an air

2

screw comprised of a plurality of blades, constructed in accordance with the instant inventive concept.

Similar reference characters refer to similar parts throughout the several views of the drawings.

Having reference now to the drawings, there is generally indicated at 10 a drive shaft of any desired conventional type, and operated by any desired suitable source of power, on which is mounted a spider generally indicated at 11. The spider 11 includes a plurality, illustratively 4 arms 12 extending radially therefrom, on which are mounted beveled ring gears 13, the gears being freely rotatable thereupon. Suitable cap-members 14' are provided adapted to hold the gears in related assembly with the spider. The gears 13 are adapted to engage oppositely disposed beveled ring gears 14, each journaled for rotation about the shaft 10, and secured in position by means of thrust collars 15 secured to the shaft 10 as by set-screws 16. Each of the ring gears 14 has secured thereto as by means of laterally extending threaded stems or bolts 17 provided with nuts 18, annular rings 19, each of which rings is adapted to provide a hub for a propeller, the fragments of the blades of which are indicated at 20 and 20' in Figure 1. The extremities of the spider 11 and the caps 14' are likewise adapted to support an annular ring 21, on which are mounted blades 22, comprising still a third propeller.

From the foregoing the method of operation of the device should now be readily understandable. As the drive shaft 10 is rotated, the spider 11, and hence the gears 13 are correspondingly rotated. The rotation of the gears 13 correspondingly rotate the associated ring gears 14, and through the bolt and nut connection previously described accordingly rotate the annuli 19 and the propeller blades 20 and 20'.

As best shown in Figure 3, the blades 20, 20' and 22 are preferably of different diameters, the arrangement being such that the successively smaller blades rotate within a radius of rotation of the larger blades, in such manner as to produce an increased efficiency in the area of lowered efficiency of the larger blades.

Obviously, any desired number of blades may be positioned on the drive shaft, and the pitch and dimensions of the blade may be varied according to the use to which the device is to be put.

As many embodiments may be made of this inventive concept, as many modifications may be

made in the embodiment hereinbefore shown and described, it is to be understood that all matter herein is to be interpreted merely as illustrative and not in a limiting sense.

I claim:

1. In a multiple air screw, in combination, a rotatable shaft, a spider fixed on said shaft between its ends and having radial arms, beveled gears carried by said arms, a ring gear driven by said beveled gears, blades mounted on said spider, and blades secured to and rotatable by said ring gear.

2. In a multiple air screw, in combination, a shaft, a spider on said shaft, beveled gears carried by said spider, a pair of oppositely disposed ring gears driven by said beveled gears, blades carried by said spider, and blades secured to and rotatable by each of said ring gears.

3. In a multiple air screw, in combination, a shaft, a spider fixed on said shaft intermediately of its length and having radial arms, beveled gears carried by said arms, ring gears driven by said beveled gears on said shaft on opposite sides of said spider and driven by said beveled gears, blades secured to said spider, and blades secured to and rotatable with said ring gears, said blades being of different diameters.

4. In a multiple air screw, in combination, a shaft, a spider on said shaft, beveled gears carried by said spider, a pair of oppositely disposed ring gears driven by said beveled gears, blades carried by said spider, and blades secured to and rotatable by each of said ring gears, each of said blades being of a different diameter.

5. In a multiple air screw, in combination, a shaft, a spider on said shaft, beveled gears carried by said spider, a pair of oppositely disposed ring gears driven by said beveled gears, blades carried by said spider, and blades secured to and rotatable by each of said ring gears, each of said blades being of a different diameter and different pitch.

6. In a multiple air screw, in combination, a shaft, a spider on said shaft, beveled gears carried by said spider, a pair of oppositely disposed ring gears driven by said beveled gears, blades carried by said spider, blades secured to and

10

rotatable by each of said ring gears, each of said blades being of a different diameter and different pitch and means for rotating said drive shaft to rotate all of said blades in a common direction.

7. In a multiple air screw, a shaft, a spider fixed on said shaft between its ends and having integral radial arms, beveled gears carried by said arms for rotation thereon, ring gears driven by said beveled gears and having outwardly extending sleeves fixed on the shaft on opposite sides of the spider and beveled gears, blades secured to said spider and blades secured to and rotatable with said ring gears.
